Primary Examiner — Ralf Seifert(74) *Attorney, Agent, or Firm* — Douglas B. Farrow(57) **CLAIM**

The ornamental design for a plural component proportioner, as shown and described.

DESCRIPTION

FIG. 1 is a front isometric view of a plural component proportioner showing our new design;

FIG. 2 is a front view thereof;

FIG. 3 is a left side view thereof;

FIG. 4 is a rear side view thereof;

FIG. 5 is a right side view thereof;

FIG. 6 is a top view thereof; and,

FIG. 7 is a bottom view.
